LAUNCHING DEVICE FOR FIRING
PROJECTILES FROM A MORTAR

Otha R. Roderick, Cumberland, Md.

Application July 15, 1947, Serial No. 761,033

4 Claims. (Cl. 89—1)

1

This invention relates to ammunition and more particularly to a novel launching device for firing projectiles from a mortar. Prior to the present invention small mortars, particularly those used for projecting shells containing chemicals were originally fired by dropping the projectile into the muzzle end of a smooth bore barrel, letting it slide down to the breech end of the barrel, where it would contact a fixed firing pin which acted to fire it back through the barrel. For firing at low elevations, this procedure was improved by providing a driver device comprising a small rocket charge attached to the nose of the projectile by means of an adapter. This driver contained a firing pin, provided with a pull ring. In operation the projectile was laid in the muzzle of the mortar where it would rest due to the previously adjusted low elevation of the barrel. The gunner would then actuate the firing pin of the driver by means of the pull ring and the explosion of the driver charge would propel the shell down into the breech end of the barrel where it would strike the fixed firing pin and be repropelled out of the barrel. These and other prior procedures involved considerable hazard due to the fact that the non-uniform area of the blast at the mortar frequently endangered the gunner.

The primary object of the present invention is to eliminate these and other hazards by means of an improved launching device for projectiles. Another object is to provide such a device that will hold a projectile in a muzzle even when elevated or depressed. An additional object is to provide such a device that can be operated from a position outside the area of blast of a gun. A further object is to provide such a device that will simultaneously release the projectile and fire the driver charge. Other equally important objects will more plainly appear from the detailed drawings and specification presented in exemplification but not in limitation of the present invention. Like reference characters represent like parts in the drawings which illustrate diagrammatically in

Fig. 1, a side elevation of the end portion of the muzzle of a mortar having attached thereto the launching mechanism shown partly in longitudinal cross section and in engagement with a projectile and its repelling charge.

Fig. 2, a bottom view of the assembly shown in Fig. 1.

Fig. 3, an end elevation thereof viewed toward the muzzle.

A preferred embodiment of the present inven-

2

tion is shown in Fig. 1. The launching device 15 is shown attached to the muzzle 14 of a gun barrel by retaining bands 12 and adjusting bolts 16. The projectile 10 is shown in its operating position protruding from the muzzle 14 of the gun and having attached thereto by means of the adapter 40 its repelling driver 29, which contains a suitable rocket charge, arranged to force projectile 10 to travel inwardly in the gun barrel. 10 The body member 38 contains motor means preferably comprising a main spring housing 21 fitted with a buffer member 17 of resilient material, and a main operating spring 25. Attached to the body 38 is a hand grip 22, the trigger safety lock 23 and trigger 24 pivoted at 18, and provided with an extension arm 19 urged into engagement with the sear 26 by means of the sear spring 11. Spring 11 is held in adjustment in housing 46 by means of adjusting screw 47, so that spring 11 will be in operative relationship with arm 19.

A cocking arm 13 extends rearwardly from yoke 27 in the rear pivot 20. Yoke 27 extends under the nose of the shell 10, and operates on pivots 20 and 20' as shown in Fig. 3. The yoke 27 is provided with a spur or lip 36 which is adapted to engage the annular groove 45 in the repellent adapter 40 as shown in Fig. 1. If desired the adapter 40 may be so designed that 25 when attached to the shell 10 it will form an annular groove between the nose of the shell 10 and the adapter. The yoke 27 is also provided with a ring trigger 37 extending outwardly from lip 36 and arranged to project through the pull ring 28. Extending downwardly from the yoke 27 is the sear arm 31 which is fixed to the sear 26 and which is connected to the piston rod 33 at the pivot 32. The piston rod 33 is pivoted at 34 to the piston 35 which acts as a retaining 30 means for the main spring 25 in the housing 21. The trigger lock 23 is pivoted at 43 and provided with the catch 41 also pivoted at 43. Adjustable lock control means is shown at 42 arranged to coact with the lock 23 so that it will hold the 35 trigger 24 in proper operating position until the lock 23 is disengaged. The trigger 24 is provided with a guard member 44 which also protects the lock 23 and spring 11.

In operation the projectile 10 is laid in the gun muzzle 14. The gunner presses downwardly on the cocking arm 13 so that the yoke 27 is elevated through pivots 20 and 20' until it engages the shell retaining lip 36 in the annular notch 45 in the driver adapter 40. At the same time the ring trigger 37 is positioned beneath the

repelling driver 29 so that the gunner may then slip the pull ring 28 over the trigger 37. Concurrently the sear 26 moves into its forward position as shown in Fig. 1, and spring 11 urges arm 19 into engagement with sear 26, which holds spring 25 in compression. Yoke 27 will now securely hold the projectile 10 in the gun muzzle 14 even though it is elevated above or depressed below the horizontal position.

In order to launch the projectile 10 inwardly into the gun barrel the gunner releases the safety lock 23 with his thumb and squeezes the trigger 24, which acting through its pivot 18 depresses the extension arm 19 and releases its engagement with the sear 26. This permits the main spring 25 to instantly expand and thrust piston 35 back against buffer 17. This thrust acting through rod 33, pivots 34 and 32, and the arm 31, causes the simultaneous depression of the yoke 27 on its pivots 20 and 20'. This releases the lip 36 from the groove 45 and depresses the ring trigger 37, which acting against the pull ring 28 withdraws the firing pin 38 from the repelling driver 29. This explodes the rocket charge in the repellent 29 which forces the projectile 10 down from the muzzle 14 to the breech end of the barrel of the mortar where it strikes the firing pin therein and is propelled outwardly in the usual manner.

It will be seen that the present invention enables the gunner to grip the trigger 24 while standing well outside of the blast area whose forward limit is indicated at the line 39. This affords added protection from any accidental injury therefrom, permits greater accuracy in aiming, and increases the rate at which the mortar may be fired.

While applicant has presented the foregoing description of his improved launching mechanism in detail with respect to a preferred embodiment thereof, he does not contemplate limitation thereto, but does include all forms and modifications thereof within the spirit and scope of the appended claims.

What is claimed is:

1. A launching mechanism arranged for cooperative relationship with a gun barrel, a projectile, and projectile repellent means attached to the nose of said projectile, said launching mechanism comprising in combination a body member, means for attaching said body member

5 to said barrel, retaining means for holding said projectile in a protruding position in the muzzle portion of said barrel, said retaining means including a yoke member adapted to cradle the nose of said projectile, pivot means for said yoke member positioned on opposite sides of said body member, motor means for depressing said yoke member, means cooperating with said yoke member for energizing said motor means, lever means for actuating said motor means, means for releasing said projectile, and means co-acting with said yoke member for concurrently firing said repellent means upon the operation of said release means.

15 2. A launching mechanism arranged for cooperative relationship with a gun barrel, a projectile, and projectile repellent means attached to the nose of said projectile; said launching mechanism comprising in combination: a body member; means for attaching said body member 20 to said barrel; projectile-retaining means pivoted on said body member and arranged to cradle the nose of said projectile in a protruding position in the muzzle portion of said gun barrel; motor 25 means for releasing said retaining means from said projectile; trigger means for actuating said motor means; and means for concurrently firing said repellent means upon the operation of said trigger means.

30 3. The combination of claim 2 wherein said retaining means includes a yoke member arranged to cradle the nose of said projectile in a manner that prevents the forward or rearward movement of said projectile in said barrel while said yoke is in engagement with said projectile.

35 4. The combination of claim 2 that includes means for energizing said motor means, and trigger means arranged to concurrently actuate said motor means and said repellent means.
